UNITED STATES PATENT OFFICE.

FRANK M. HENDERSON AND JAMES A. PETTIBON, OF ALLIANCE, OHIO.

TURBINE.

1,096,368.

Specification of Letters Patent.

Patented May 12, 1914.

Application filed October 30, 1911. Serial No. 657,694.

To all whom it may concern:

Be it known that we, FRANK M. HENDERSON and JAMES A. PETTIBON, citizens of the United States, residing at Alliance, in the county of Stark and State of Ohio, have invented a new and useful Turbine, of which the following is a specification.

Our invention relates to improvements in turbines and especially to that class of turbines peculiarly adapted to be operated by the expansion of gases of combustion.

The objects of our invention are to generally improve devices of the character mentioned and to provide a simple, durable and easily made turbine so constructed that it will not readily get out of order, will need the minimum attention and repairing, and may be readily adapted to a great number of practical uses, efficiency and thorough practicability being also objects of importance. These objects, together with other objects apparent to those skilled in the art, may be attained by the construction illustrated in the accompanying drawings, although the invention may be embodied in other forms, the construction illustrated being chosen by way of example.

In the drawings, Figure 1 is a vertical longitudinal sectional view of a turbine embodying our invention. Fig. 2 is a front end elevation of the same. Fig. 3 is a side elevation of the same. Fig. 4 is an enlarged sectional view of the valve and ignition chambers and the parts immediately related thereto. Fig. 5 is a top plan view of the turbine. Fig. 6 is a view showing in elevation one of the stationary vane sections. Fig. 7 is an enlarged fragmentary sectional view of one of the stationary vane sections taken on a plane parallel to the shaft of the turbine. Fig. 8 is a view in elevation of one-half of a rotatable vane section, parts being broken away to disclose the construction. Fig. 9 is an enlarged fragmentary sectional view of one of the rotatable vane sections taken on a plane parallel with the shaft of the turbine. Fig. 10 is an elevation of one-half of the nozzle head showing nozzle apertures arranged therein. Fig. 11 is a sectional view on line 11-11 of Fig. 10. Fig.

12 is a fragmentary perspective view of the cam shaft and cams thereon.

Throughout the several views similar reference numerals indicate similar parts.

The numeral 1 indicates the lower section and the numeral 2 the upper section of the turbine casing proper, said sections being provided with the outstanding flanges 3 connected by the bolts 4. The lower section is provided with the front end wall 5 and the rear end wall 6 while the upper section is provided with the front end wall 7 and the rear end wall 8, which walls 5 and 7 and 6 and 8 respectively are provided with complementary portions of bearings to receive the rotatable main shaft 9, concerning which more will hereinafter be stated.

Both the lower section 1 and upper section 2 of the casing are generally speaking semi-cylindrical, the internal diameter of said casing being smaller adjacent the front end of the device and larger adjacent the rear end of the device, the end of smaller diameter being the high pressure portion and that of greater diameter being the low pressure portion. In case a greater expansion turbine is made in accordance with our invention, there would be portions of said sections of even greater diameter than the large diameter shown in the drawings as will be well understood by those skilled in the art.

The lower section 1 is preferably provided with the integral base portions 10 and 11 by means of which the device is intended to stand firmly upon an appropriate foundation, but it will be understood that said base portions form no part of the invention claimed herein, as the casing may be supported in various other ways. Connected to the front wall 5 of the lower section is a bracket 12 supporting a bearing 13 adapted to receive the shaft 9 and at the back end of the device the support 14 connected to the end wall 6 is similarly provided with a bearing 15 also receiving the shaft 9. The bearings 13 and 15 are preferably spaced from the front and rear walls respectively and are adapted to support the shaft 9, very little of the weight of said shaft being imposed upon the bearings formed in the end walls, 100

the said bearings in said walls however being provided with close fitting packing 16 to prevent escape of gas from the interior of the casing when the turbine is in operation.

5 On the interior of both lower and upper sections are arranged a plurality of circumferentially disposed, stationary vane sections such as illustrated in Fig. 6. Each section comprises a semi-circular vane base 17 adapted to conform to the inner curved surface of the casing section and a plurality of stationary vanes 18 fixedly connected at their outer ends to said base. In Fig. 7 an end view of some of the stationary vanes 18

10 is given and it will be seen that said vanes are curved in cross section about axes perpendicular to the axis of the turbine casing, said vanes being arranged in an annular series and preferably somewhat closer together than shown in the drawings. In the high pressure portion of the turbine the bases 17 are of relatively small diameter to fit the smaller diameter of the casing whereas the vane bases in the low pressure portion are of

15 greater diameter. The stationary vanes 18 in the high pressure portion are also shorter than the corresponding vanes in the low pressure portion so that considering all of the stationary vanes in the turbine their inner ends extend to practically the same distance toward the shaft 9 as well illustrated in Fig. 1.

Fixedly mounted upon the shaft 9 are the rotary vane sections, each of which is provided with the rotary vane base 19 comprising a hub portion 20 mounted on the shaft 9 and an integral annular extended portion 21 provided at its periphery with a dove-tailed groove formed by the integral portion 22 on the one side and a removable ring 23 on the other side, the periphery of the portion 21 constituting the bottom of the groove. Each ring 23 is held in place by an annular series of bolts 24, each of which 40 bolts extends through the base 25 of one of the rotary vanes 26. This construction is well illustrated in Figs. 8 and 9 as well as in Fig. 1 and it should be noted that the vanes 26 are fixedly connected to their respective bases 25 and arranged in annular series about the portion 21, the bases 25 completely filling the dove-tailed groove heretofore mentioned. The vanes 26 are of different lengths to correspond to the difference 45 in diameter of the turbine casing, it being preferable that said vanes extend to points adjacent the walls of the sections 1 and 2.

It will be noted that the vane bases 17 are provided with inclined edges, producing a 50 dove-tailed shape in cross-section, and in assembling the device said bases may be arranged on the inner sides of the sections of the casing and held in place by the spacing, retaining rings 27 which are provided with

edges inclined oppositely from the edges of the bases 17, so that the resulting construction is that shown clearly in Fig. 7 where it will be seen that the bases 17 are held firmly and fixedly in place by the rings 27.

The hub portions 20 of the rotary vane bases are of such length as to bring the various rotary vane sections intermediate stationary vane sections, the first rotary vane section however in the high pressure portion of the device being in front of the first stationary vane section and the last rotary vane section in the low pressure portion being beyond the last stationary vane section.

Extending between each two rotary vane bases is a substantial band 28 having its 80 opposite edges fitted into annular grooves in the portion 21 and ring 23 respectively in each instance, said band 28 being so located as to rotate with the rotary vane sections adjacent the inner ends of the stationary vanes 85 18. This construction is clearly illustrated in Fig. 1.

Each of the vanes 26 is curved about an axis coincident with one of the radii of the rotary vane section, as illustrated in Figs. 8 and 9 and in accordance with well known turbine construction. It is to be noted in this connection that the vanes 18 and the vanes 26 are curved in opposite directions to produce a tortuous course of the operative 95 gases in their action upon said vanes.

On the inside of the turbine casing, rearwardly spaced from the front end wall thereof, and closely adjacent the first rotary vane section is the nozzle head 29, which is provided in its upper portion, adjacent its outer edge with one or more nozzles 30 which, in the simplest form, may consist of tapered apertures leading obliquely through said head and adapted to direct gases passing forcibly therethrough against the vanes 26 of the first rotary vane section. On the inner side of the upper section 2 is arranged the nozzle-supplying duct 31 having communication only with the nozzles 30 and an outer, entrant portion 32 concerning which more will presently be stated. Located within the space between the nozzle head and the front end wall of the casing the fly wheel 33, preferably of considerable 100 weight, is fixedly mounted upon the shaft 9 for the purpose of producing smooth and even running of the device under varying conditions of gas pressure and load, while at the same time steadyng the shaft 9 against 110 endwise movement during the operation of the turbine.

Extending frontwardly beyond the bearing 13 the shaft 9 is provided with the fixedly mounted sprocket 34 and the fixedly mounted fan 35. The purpose of the sprocket 34 will hereinafter more fully appear. The purpose of the fan is for the

production of a draft of air against the turbine casing to prevent the over-heating thereof. Extending rearwardly beyond the bearing 15 the said shaft 9 is provided with 5 the sprocket 36 and the beveled gear 37. Connected to the rear end wall of the turbine casing, and having communication therethrough with the interior of said casing is the exhaust fan 38 adapted to be 10 operated by means of the chain 39 passing over the sprocket 36 on the main shaft. When the main shaft rotates rapid rotation of the fan 38 is produced, said fan being adapted to exhaust gases from the interior 15 of the casing, discharging the same through the exhaust aperture 40 in the fan casing.

For the purpose of supplying combustible gas to the turbine some source of gas or gasolene should be available. In the drawings we have illustrated that form of the device in which gasolene is to be used for the production of gas, the pipe 41 being connected to the gasolene supply. Connected to the pipe 41 is the carbureter 42, of any 20 well known design provided with the throttle 43 which is adapted to be turned so as to increase or decrease the quantity of gasolene vapor obtainable from the carbureter, in accordance with well known construction. 25 From the carbureter runs the pipe 44 provided with a check valve 45 of well known design so constructed as to prevent any backward flow of vapor into the carbureter. Extending rearwardly from the check valve the 30 pipe 44 leads into the pump cylinder 46 which is fixedly connected to the lower section 2 and is provided with the piston head 47. Supported by the bracket 48 is the shaft 49, rotatably mounted in the bearings 40 50 on said bracket. Fixedly mounted on said shaft at one end the beveled gear 51 meshes with the beveled gear 37 while at the other end of the shaft 49 is fixedly mounted the disk 52 provided with the crank pin 53 45 to which is connected the reciprocating pitman 54, to which the piston head 47 is connected. It will be obvious that as the shaft 9 rotates the pitman 54 will be caused to reciprocate; thus moving the piston head 47 50 backward and forward in the cylinder 46, each forward movement of said piston being 55 adapted to draw gasolene vapor into said cylinder from the carbureter 42 and through the check valve 45. Upon the backward movement of the piston 47, the check valve 45 closing, the vapor will be forced outwardly through a second check valve 55 and into the pipe 56.

As hereinbefore stated the entrant portion 0 32 is connected to the nozzle supplying duct 31 with which, in fact, it is continuous. Arranged upon the outside of the turbine casing where said entrant portion 32 opens outwardly through said casing are arranged

the valve and ignition chambers which consist of a receiving and compressing chamber 57 into which the pipe 56 leads, said chamber being adapted to receive gasolene vapor under pressure from the pump cylinder 46. In the upper wall of the chamber 70 57 are two valve openings 58, each adapted to be closed by a valve 59 and each, when open, leading into an ignition chamber. One of said ignition chambers is designated 60 and the other 60^a. In the top wall of each 75 of said ignition chambers is arranged a removable cap 61 provided with a spark-plug 62 of well known construction, said spark plug extending through said cap and into the ignition chamber, in the manner well 80 known to those skilled in the art. In the side wall of each ignition chamber is arranged a valve opening 63, normally closed by a valve 64, but when open providing communication between the interior of the ignition chamber and the entrant portion 32 of the nozzle supplying duct 31. For the purpose of normally holding the valves 64 in closed position in the openings 63, said valves are mounted upon stems 65 extending 85 across the ignition chambers, through the opposite walls of said chambers, and provided externally with a compressible spring 66 adapted to yield when gas is exploded in the ignition chamber, to permit the exhaust 90 of said gas through the valve opening 63 into the nozzle supplying duct.

Each of the valves 59 is mounted upon a valve stem 67, said valve stems extending downwardly and through the bottom wall 100 of the receiving chamber 57 and provided with springs 68, adapted to normally hold the valves in closed position, but adapted to yield to a forcible upward movement of the stems 67 to permit the valves 59 to be lifted 105 or opened.

Rotatably mounted in the bracket bearing 69 attached to the lower section 1 is the valve and commutator shaft 70 to which, at its forward end is fixedly connected the 110 sprocket 71 over which passes a chain 72, also engaging the sprocket 34, so that by rotation of the main shaft 9 the shaft 70 will be rotated.

Fixedly mounted upon the shaft 70 is the 115 cam 73, the peripheral face of which is engaged by the lower end of the stem 67 connected to the valve 59 in the ignition chamber 60^a. For the purpose of reducing friction the lower end of the stem 67 may be 120 provided with a roller 74 engaging the cam 73 in a manner well known to those skilled in the art. The cam 73, as the shaft 70 rotates, will reciprocate the stem 67, thus raising and lowering the valve 59 to alternately open and close the valve opening 58 between the receiving chamber 57 and the ignition chamber 60^a. The stem 67 con-

trolling the valve 59 for the chamber 60 is reciprocated in a similar manner by the cam 75 which is mounted upon the shaft 70 so as to rotate with said shaft but at the same time is slidably longitudinally therealong. This is accomplished by means of a feather key 76 which extends for some distance along the shaft 70, as will be well understood by those skilled in the art.

10 Formed integrally with the cam 75 is the round portion 77, the periphery of which is concentric with the shaft 70. When it is desired to reciprocate the valve stem 67 for the chamber 60 the cam is slidably moved 15 along the shaft 70 into the position shown in Fig. 4, but when it is desired that said stem shall not be reciprocated, under the circumstances hereinafter mentioned, the cam may be slidably moved along the shaft 20 70 so as to bring the round portion 77 under the end of the stem, which will permit the stem to remain stationary. It should be stated that in the normal operation of the device the cam 73 and cam 75 are oppositely 25 disposed, or so arranged upon the shaft that the two valves 59 will be alternately opened and closed. As shown in Fig. 12 the cams 73 and 75 are cut away in such manner that while the stems 69 are gradually and slowly 30 raised, when the extreme limit of raising movement has been reached, the stems will be permitted to drop or jump back, thus seating the valves instantly.

Supported upon a bracket 78 is a magneto 35 79 and a commutator 80. Both magneto and commutator are operatively connected to the shaft 70, the magneto having one side of its circuit grounded on the turbine and the other side of the circuit carried to the commutator by the wire 81 in the manner well known to those skilled in the art. From the commutator the wires 82 and 83 lead to the two spark plugs so that the plugs may be sparked alternately as is 40 common in explosive engine construction.

45 The operation of the device is as follows: The shaft 9 being started to rotate, gasolene vapor will be drawn into the cylinder 46 from the carburetor and, by the movement 50 of the piston head 47 will be forced through the pipe 56 into the receiving and compressing chamber 57. By the continuous operation of the device said chamber 57 will thus be continually supplied with an explosive 55 mixture under pressure. By the rotation of the shaft 70 this explosive mixture will be permitted, under its pressure, to enter the chambers 60 and 60^a alternately. Immediately after a charge has thus entered 60 one of said chambers, the valve 59 will instantly close, whereupon the commutator 80 will cause the spark plug of that ignition chamber to explode the charge therein. The exploding charge will force open the valve

64, against the tension of the spring 66, thus permitting the charge to enter the entrant portion 32 and thence into the nozzle supplying duct 31. Having entered the nozzle supplying duct the expanding gases will rush through the nozzles 30 with great force 70 against the rotary vanes 26 of the first rotary vane section, thence between the stationary vanes 18 of the first stationary vane section, which will properly direct the gases 75 against the rotary vanes of the second rotary vane section, and so on through the series of stationary and rotary vanes. At the same time the exhaust fan 38 will be rapidly rotated to assist in the exhaust of the used gases from the rear end of the casing, 80 the fan 38 thus acting to assist in overcoming atmospheric pressure upon somewhat the same principle as the condenser of a condensing engine. By proper manipulation 85 of the throttle 43 the power and speed of the turbine may be regulated, and if desired the cam 75 may be moved along the shaft 70 so as to discontinue the opening and closing of the valve 59 into the ignition chamber 60, thus employing only one 90 ignition chamber in cases where low speed or less power are desired.

Attention should be called to the fact that all moving parts which would require attention or adjustment and all parts requiring lubrication are arranged externally with reference to the turbine casing, the parts enclosed requiring substantially no attention at all. All moving parts requiring attention are readily accessible and may be easily 100 and quickly repaired. These desirable features as well as many others will recommend the hereinbefore described construction to those who are skilled in the art.

105 We claim:—

A turbine comprising a substantially cylindrical casing formed of two hollow segmental portions and provided with front and rear end walls, a rotor shaft extending axially through said end walls, bearings for 110 said shaft outside of said casing and spaced beyond said end walls, stationary vane sections fixedly connected to said casing, rotary vane sections fixedly connected to said shaft and adapted for coöperation with said 115 stationary vane sections, the first of said vane sections spaced from said front end wall, a fly wheel fixedly mounted on said shaft on the inner side of said front end wall, explosive gas supplying means, a receiving and compressing chamber, pumping means operatively connected to said 120 shaft for pumping said gas from said supplying means into said chamber, a plurality of ignition chambers, valved openings from said receiving and compressing chamber to the several ignition chambers, operative means actuated by said shaft for me-

chanically, consecutively opening and closing the valves of said several openings, openings from said several ignition chambers into the interior of said casing intermediate said fly wheel and said first vane section, valves normally closing the last mentioned openings and adapted to be opened by explosions in said ignition chambers, and igniting means in said ignition

10 chambers.

In testimony that we claim the above, we have hereunto subscribed our names in the presence of two witnesses.
